Primary Examiner—T. Chase Nelson*Assistant Examiner*—Michael A Pratt(74) *Attorney, Agent, or Firm*—Barlow, Josephs & Holmes, Ltd.(57) **CLAIM**

The ornamental design for a weapon handguard, as shown and described.

DESCRIPTION

FIG. 1 is a perspective view of the weapon handguard in accordance with the present invention;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The recessed portions on FIGS. 1 and 5-7 shown in broken lines are included for the purpose of illustrating the environment and form no part of the claimed design.
